UNITED STATES PATENT OFFICE.

GEORGE AARON SMITH, OF ROCKLAND, MASSACHUSETTS.

SHOE.

SPECIFICATION forming part of Letters Patent No. 331,833, dated December 8, 1885.

Application filed September 19, 1885. Serial No. 177,559. (No model.)

To all whom it may concern:

Be it known that I, GEORGE AARON SMITH, of Rockland, in the county of Plymouth, of the Commonwealth of Massachusetts, have 5 invented a new and useful Improvement in Shoes; and I do hereby declare the same to be described in the following specification and represented in the accompanying drawings, of which—

10 Figure 1 is a top view, and Fig. 2 a side elevation, of a shoe of my invention, the nature of which is defined in the claim hereinafter presented.

It consists in a shoe having its upper composed of leather crimped or stretched into form in the instep portion thereof, and afterward slit down the middle of the stretched part to make in it an instep-opening, there being in the upper near to each edge of such 20 opening a series of holes provided with eyelets for receiving a lacing, the ends of the said upper extending to the middle of the back of the heel, and there being secured or sewed together.

25 In the drawings the upper of the shoe is shown at *a*, the sole at *b*, and the heel at *c*. The leather composing the upper is first cut in the requisite form for being crimped, so as to cause the upper, when on the foot of a person, to be suitably raised over the instep thereof. Next such leather is to be crimped or stretched transversely in other respects

upon a suitable form and to the necessary extent to give to it the required instep-rise, after which it is to be slit or cut down through 35 the middle of such rise, as shown at *d*. Subsequently there is to be made in the upper near such edge of the slit a series of lacing-holes, *e*, into each of which an eyelet may be inserted. The ends of the upper are next to 40 be stitched or seamed together at and down the middle of the back of the heel, such serving to stiffen the upper at such back, and to prevent or aid in preventing it from then breaking down or wrinkling while the shoe 45 may be in wear. The upper thus made is to be lined, finished, and fixed to an insole and an outer sole in the usual manner.

I do not claim, broadly, a shoe having an instep-opening formed in its upper without such upper being crimped, as described.

I claim—

As an improved article of manufacture, a shoe having its upper of a single piece of material crimped into form in the instep portion 55 thereof, and slit down the middle of such portion, and provided with lacing-holes and a lacing, and having its ends extending to and seamed together at the middle of the back of the heel, all substantially as set forth.

GEORGE AARON SMITH.
